SPECIFICATION forming part of Design No. 13,158, dated August 8, 1882.

Application filed June 12, 1882. Term of patent 3½ years.

To all whom it may concern:

Be it known that I, WILLIAM R. McCOMAS, a citizen of the United States, residing at Oakley, county of Hamilton, and State of Ohio, have produced a new and original Design or Emblematic Ornament for the Bracket Supporting the Handle of a Coffin or Burial-Case, of which the following is a specification, reference being had to the accompanying drawing.

My invention is an emblematic ornament for the bracket supporting the handle of a coffin or burial-case; and it consists in the head and bust of an angel surrounded by the closed wings and the head surmounted by a star.

Having thus described my invention, what I claim as new, and desire to secure by Letters Patent, is—

An ornamented lug or handle-bracket for coffins, consisting of the head and bust of an angel surrounded by the closed wings, as described.
